UNITED STATES PATENT OFFICE.

EARL VAUGHAN, OF BEVERLY, MASSACHUSETTS.

STEAM-ENGINE INDICATOR.

1,098,067.

Specification of Letters Patent. Patented May 26, 1914.

Application filed September 12, 1912. Serial No. 720,097.

To all whom it may concern:

Be it known that I, EARL VAUGHAN, a citizen of the United States of America, and a resident of Beverly, in the county of Essex and State of Massachusetts, have invented 5 certain new and useful Improvements in Steam-Engine Indicators, of which the following is a specification.

This invention relates to improvements in 10 engine indicators and has for its particular object the production of a device of this class in which a continuous strip of paper is adapted to be intermittently moved for the purpose of having recorded thereon a continuous 15 series of diagrams showing the successive strokes of the engine to which said indicator is applied.

The invention consists in certain novel 20 features of construction and arrangement of parts which will be fully understood by reference to the description of the drawings and to the claims hereinafter given.

Of the drawings: Figure 1 represents an elevation of a device embodying the features 25 of the present invention, a portion of the strip of paper being broken away. Fig. 2 represents a plan view of the same. Fig. 3 represents a section of a portion of the same, drawn to an enlarged scale, the cutting plane being on line 3—3 on Fig. 2. Fig. 30 4 represents a horizontal section of the oscillating drum, the cutting plane being on line 4—4 on Fig. 3. Fig. 5 represents a plan view of the base ring for said oscillating 35 drum. Fig. 6 represents a portion of the locking device for preventing the operation of the paper feeding devices during the normal oscillation of the drum. Figs. 7 and 40 8 represent respectively an inverted plan and a plan of two parts of the clutch mechanism interposed between the oscillating drum and the spool for receiving the strip of paper. Fig. 9 represents an elevation partially in section of the delivery spool for 45 said strip of paper. Fig. 10 represents a horizontal section of the same, the cutting plane being on line 10—10 on Fig. 9. Fig. 50 11 represents an elevation of a portion of the paper strip showing indicator cards 55 corded thereon, and Figs. 12 and 13 represent diagrams showing the extreme positions of the paper strip during the oscillatory movement of said drum.

Similar characters designate like parts 55 throughout the several figures of the drawings.

In the drawings, 10 represents an indicator cylinder of any usual construction, which at the lower end is provided with the usual hand nut 11 having handles 12 by 60 which said nut is turned in securing the indicator to the indicator cocks provided for that purpose on the engine cylinder. The upper end of the cylinder is provided with a support 13 for the indicator marking 65 arm 14, and is rotatably secured in position by means of the removable cylinder cap 15. The cylinder 10 is provided with the usual piston which is not shown, as this portion of the device forms no part of the present 70 invention. To said piston is secured a piston rod 16 the upper end of which extends through the cylinder cap 15 and is secured by means of the screw 17 to the marking 75 arm 14 pivotally connected at 18 to the link 19. This marking arm is also connected by means of the link 20 to the standard 21 secured to the support 13. A pencil or other marking device is provided at 22. Projecting from the cylinder 10 and preferably 80 formed integral therewith is a support 23 having secured thereto a plurality of uprights 24, to the upper end of which is fastened a plate 25. Secured to the upper face of the support 23 are brackets 26, 26^x, 85 and interposed between the plate 25 and the brackets 26, 26^x are the revoluble paper carrying spools 27 and 28. The spool 27 is the delivery spool while the spool 28 is adapted to receive the strip of paper 29 90 delivered from the spool 27 when fed. The spool 28 has depressions at either end in the upper of which extends a projection 30 formed upon the flanged threaded member 31 mounted in the plate 25 and secured in 95 position by the locknut 32. Into the depression in the lower end of said spool 28 extends a projection 33 formed upon a conical friction clutch member 34 positioned in a depression in the revoluble member 35 to 100 which is secured the cup-shaped retaining ring 36 to prevent the displacement of said conical clutch member 34. This member 35 is provided with a spindle 37 revolubly mounted in the bracket 26 and having secured thereto a pinion 38. This pinion 38 meshes with the teeth of a gear 39 formed upon the periphery of a revoluble member 40 mounted upon a stud 41 fixedly secured to the support 23. The member 40 has a 110 depression in its upper face in which is mounted the spring pressed pawls 42 adapt-

ed to engage the teeth of a ratchet 43 positioned within said depression and secured to a top plate 44 also revolubly mounted upon the spindle 41. This top plate 44 is provided with gear teeth 45 on its periphery which are adapted to engage the gear teeth 46 formed upon the drum support 47. Threaded to this drum support 47 is an annular member 48 supporting an inner cylinder 49 and an outer cylinder 50 separated at their upper ends by means of the annular member 51. The inner cylinder 49 surrounds a support 52 of any well known construction extending upwardly from a housing 53, inclosing the usual drum operating spring 54, said housing 53 being secured by means of the pin 55 to the grooved member 55 to which the operating cord *a* is secured. The grooved member 55 is adapted to be revolved about the cylindrical extension 56 secured to the support 23 by means of the nut 57 threaded to the shank 58 thereof in the usual manner.

Surrounding a downwardly extending cylindrical portion of the annular member 48 is a gear 59 the hub of which has rigidly secured thereto a ratchet wheel 60. The ratchet wheel 60 is adapted to be engaged by the pawl 61 pivotally mounted upon a stud 62 and secured to an arm 63 of the support 23. The pawl 61 is provided with an extension 64 normally engaging a cam member 65 revoluble about a stud 66 fixedly secured to said arm 63. Surrounding the hub of the cam member 65 and revoluble therewith is a ratchet 67 adapted to be engaged by the spring pressed pawl 68 pivoted at 69 to a bell crank lever 70 adapted to be oscillated about the stud 66 by means of the headed rod 71. The ratchet 67 has two oppositely disposed short teeth 67 as shown in Fig. 2. A spring member 72 is coiled about both of the studs 62 and 66 in such a manner that the ends thereof act respectively upon the pawl 61 and oscillating member 70 to retain them in the normal positions as indicated in Fig. 2 of the drawings. Secured to the periphery of the annular member 48 is a cam member 73 adapted in the oscillation of the drum 50 to engage with the projecting member 74 formed upon the pawl 61 to disengage said pawl from the teeth of the ratchet wheel 60 when so engaged. Pivotally secured to the drum support 47 at 75 is a spring pressed pawl 76 in the same plane with the ratchet wheel 67, this pawl 76 being adapted to engage in the reverse movement of the drum 50 one of the teeth of the ratchet wheel 67 and return said wheel to its normal position as indicated in Fig. 2. The annular members 48 and 51 are provided with extensions thereto having bearings therein carrying the revoluble rollers 77, 78, and 79. The shafts of the rollers 78 and 79 have secured thereto

gears 80 and 81 meshing with each other, the gear 80 on the shaft of the roller 78 being adapted to be revolved by means of the gear 59 when the drum 50 is operated independently of said gear 59. The spool 27 is removably secured at its upper end by means of the threaded member 82 threaded to the plate 25 and locked by means of the nut 83 while its lower end is similarly secured to a housing 84 containing a spring 85, the tension of which serves to prevent the paper upon said spool 27 from being delivered too rapidly and acting as a takeup when the drum assumes the position shown in Fig. 13.

Mounted upon a boss 86 and extending downwardly from the plate 25 is an arm 87 connected by means of a rod 88 to a similar arm 89 surrounding an upwardly extending boss 90 formed upon the bracket 26. The arm 89 has a recess therein in which is mounted a spring 91 the outer end of which is fast to said arm 89 and the inner end fast to the boss 90, said spring being adapted to retain the rod 88 in contact with the strip of paper extending from the receiving roll 28 to the drum 50 thereby taking up any slack that there may be in the strip of paper during the oscillation of the drum 50. The strip of paper 29 extends from the delivery roll 27 over the roller or rod 77 and then around the drum 50 and between the rods or rollers 78 and 79 over a portion of the roller 77 to the receiving spool 28, all as indicated in Fig. 12 of the drawings. When the drum 50 is at the extreme of its oscillation the strip of paper assumes the position indicated in Fig. 13 of the drawings.

In the operation of the device a long strip of paper 29 is mounted upon the spool 27 as disclosed in Fig. 9 of the drawings, and this paper extends over and partially around the loose roller 77, and then partially around the drum 50, then passing between the feed rollers 78 and 79, and again over a portion of the roller 77 to the receiving spool 28. This is the normal position of the strip of paper 29. The drum is oscillated in the usual manner by means of the cord *a*, the pull upon said cord moving the drum in one direction while the spring 54 of usual construction moves the drum in the opposite direction, thereby effecting a complete oscillation of said drum. When this drum oscillates in this manner the rollers 77, 78, and 79 move therewith and at the end of the movement of said drum in one direction the strip of paper 29 assumes the position shown in Fig. 13 of the drawings. During this oscillation the strip is held fast to the drum and the takeup devices take up any slack that there may be in the paper during this oscillatory movement. The spring 85 is so connected to the spool 27 that the paper delivered therefrom is kept taut at all times,

and is only delivered therefrom when positively fed by means of the feed rollers 78 and 79. As has been described, these rollers 78 and 79 are provided with operating pinions 80 and 81 meshing with each other while the pinion 80 meshes with the gear 59 loosely mounted upon the hub of the drum 50 so that when desired this gear may be retained in a stationary position while the 10 drum is permitted to oscillate.

It is obvious that when the gear 59 is held stationary and the drum effects an oscillation in view of the fact that the rollers 78 and 79 oscillate with the drum 50 the 15 pinions 80 and 81 will be rotated during this oscillatory movement to feed the strip of paper 29, drawing it from the spool 27 against the tension of the spring 85 and delivering it to the receiving spool 28. This spool 28 will be rotated during this 20 oscillatory movement of the drum 50 by means of the gear 46 formed upon the base of said drum and meshing with the intermediate gear 44 carrying the ratchet 43 which in turn is adapted to engage the 25 pawls 42 of another gear 39 meshing with the pinion 38 secured to the shank 37 of the clutch member 35 which clutch member is adapted to impart motion to the spool 28 through the male clutch member 34 secured thereto. It is obvious that during the 30 oscillatory movement of the drum 50, while the gear 44 is oscillated in both directions it will impart movement to the gear 39 in one direction only, that is, in a direction to move the pinion 38 so that the spool 28 will wind up the strip of paper 29 as it is delivered thereto. Owing to the frictional contact 35 between the clutch members 34 and 35 the spool 28 is permitted to slip to accommodate itself to the amount of paper delivered thereto. Normally there is sufficient friction between the gear 59 and the hub of the drum 50 to cause both of these members to oscillate together, but when it is desired to feed the paper relative to the drum preparatory to marking another diagram on said strip some means must be provided for restraining the movement of said gear and 40 hold it stationary during the oscillation of the drum 50. In order to thus restrain the movement of the gear 59 the ratchet 60 is provided fixedly secured thereto. This restraining movement is effected by pressing 45 upon the push button 71 and causing the movement of the lever 70 and its pawl 68, thereby moving the ratchet wheel 67 about the axis of the spindle 66 a single tooth. This movement of the ratchet wheel 67 causes the cam member 65 secured thereto to be moved out of engagement with the finger 64, permitting the spring 72 to act upon the pawl 61 and move it into the path of the teeth of the gear 60. When this has 50 been effected and the drum 50 is oscillated

by a pull upon the cord *a* the ratchet 60 and gear 59 will be held stationary until the cam 73 secured to the drum 50 comes into contact with the projection 74 upon said pawl 61, and disengages said pawl from the 55 ratchet 60 thereby again permitting the ratchet and gear to oscillate with the drum 50. This operation will cause the strip of paper to be fed from the delivery spool 27 to the receiving spool 28 and thereby provide a clean surface upon the drum adapted to receive a new diagram. During the return movement of the drum in its oscillation the spring pressed pawl 76 will engage one of the teeth of the ratchet wheel 67 and move said ratchet wheel about the axis of the spindle 66 a single tooth. After three oscillations of the drum 50 the ratchet wheel 67 will have made a half revolution so that the cam member 65 will again have engaged the finger 64 of the pawl 61, thereby moving it about the axis of the spindle 66 out of the path of the ratchet 60. Thereafter owing to the position of the short teeth 67, out of the path of the pawl 76, the gear 59 and ratchet 60 will oscillate with the drum 50 and no further feeding of the paper will be accomplished until the push button 71 is again operated to move a long tooth 67 into the path of movement of the pawl 76, whereupon a further feeding of the paper will be effected. It must be understood, however, that during the movement of the ratchet 67 by means of the spring pawl 76 by means of three oscillations of the drum 50 in each oscillation the pawl 61 will engage with the ratchet 60 and hold it stationary until a predetermined amount of paper has been fed relative to the drum 50. The amount of paper to be 100 fed may be determined by the position of the cam 73 relative to said drum.

During the oscillation of the drum 50 a diagram may be marked upon the strip of paper as is indicated at the left of Fig. 11 110 of the drawings, or a complete card may be made thereon during two successive oscillations of the drum as indicated in the center of said figure, while, if desired, a reverse diagram may be marked thereon, as indicated at the right of said figure. It is obvious, therefore, that, with this construction, any variety of cards may be marked upon the strip of paper in such positions that they may be readily compared.

Having thus described my invention, I claim:

1. An engine indicator having rotary spools normally stationary; means for rotating said spools when desired to transfer a continuous strip of paper from one spool to the other; an oscillating drum interposed between said spools and over which said paper passes; means for always retaining the same length of paper immovable against 125

- the periphery of said drum while a diagram is being taken; a marking member arranged to mark diagrams on the paper on said drums; and means for oscillating said drum with the paper immovable to feed the paper relative thereto.
2. An engine indicator having rotary spools normally stationary but adapted to be rotated when desired to transfer a continuous strip of paper from one spool to the other; an oscillating drum interposed between said spools and over which said paper passes; a marking member arranged to mark diagrams on the paper on said drums; means for oscillating said drum in both directions with the paper immovable relative thereto while the diagram is being marked; and means for feeding said paper relative to said drum upon the completion of one diagram preparatory to making another.
3. An engine indicator having rotary spools normally stationary and carrying a strip of paper adapted to receive card diagrams; an oscillating drum over which said paper passes; means carried by said drum for normally locking said paper thereto and causing it to oscillate therewith in both directions; a marking member arranged to mark diagrams on that portion of the strip on said drum; and means for operating said locking device to permit the movement of said paper relative to said drum while being transferred from one spool to the other.
4. An engine indicator having rotary spools normally stationary and carrying a strip of paper adapted to receive card diagrams; an oscillating drum over which said paper passes; means carried by said drum for normally locking said paper thereto and causing it to oscillate therewith in both directions; a marking member arranged to mark diagrams on said strip during the oscillation of said drum; and means for operating said locking device to permit the movement of said paper relative to said drum while being transferred from one spool to the other.
5. An engine indicator having an oscillating drum and a marking member arranged to mark diagrams upon a strip of paper carried by said drum; the combination of means carried by said drum for normally retaining said strip immovable relative to said drum; and mechanism adapted to operate said retaining means to release said strip and feed it a predetermined distance during an oscillation of said drum.
6. An engine indicator having an oscillating drum and a marking member arranged to mark diagrams upon a strip of paper carried by said drum, the combination of means carried by said drum for normally retaining said strip immovable relative to said drum; and manually con-
- trolled mechanism adapted to operate said retaining means to release said strip and feed it a predetermined distance during an oscillation of said drum.
7. An engine indicator having an oscillating drum and a marking member arranged to mark diagrams upon a strip of paper carried by said drum, the combination of means carried by said drum for normally retaining said strip immovable relative to said drum; mechanism adapted to operate said retaining means to release said strip and feed it a predetermined distance during an oscillation of said drum; and means for regulating the time for stopping said feeding mechanism.
8. An engine indicator having an oscillating drum and a marking member arranged to mark diagrams upon a strip of paper carried by said drum, the combination of an annular gear surrounding said drum and movable independently thereof; a plurality of rollers carried by said drum having operating pinions driven by said annular gear and adapted to regulate the movement of said strip of paper; and mechanism for restraining the movement of said gear during an oscillation of said drum to effect the feeding of said strip.
9. An engine indicator having an oscillating drum and a marking member arranged to mark diagrams upon a strip of paper carried by said drum, the combination of an annular gear surrounding said drum and movable independently thereof: a plurality of rollers carried by said drum having operating pinions driven by said annular gear and adapted to regulate the movement of said strip of paper; mechanism for restraining the movement of said gear during an oscillation of said drum to effect the feeding of said strip; and means for returning said restraining mechanism to its normal position.
10. An engine indicator having an oscillating drum and a marking member arranged to mark diagrams upon a strip of paper carried by said drum; the combination of an annular gear surrounding said drum and movable independently thereof; a ratchet movable with said gear; a plurality of rollers carried by said drum having operating pinions driven by said gear and adapted to regulate the movement of said strip of paper; a pawl adapted to be engaged with said ratchet to prevent the movement of said annular gear during an oscillation of said drum; and means for disengaging said pawl from said ratchet at a predetermined time.
11. An engine indicator having an oscillating drum and a marking member arranged to mark diagrams upon a strip of paper carried by said drum, the combination of an annular gear surrounding said drum

and movable independently thereof; a ratchet movable with said gears; a plurality of rollers carried by said drum having operating pinions driven by said gear and adapted to regulate the movement of said strip of paper; a pawl adapted to be engaged with said ratchet to prevent the movement of said annular gear during an oscillation of said drum; and a cam on said drum for disengaging said pawl from said ratchet at a predetermined time.

12. An engine indicator having an oscillating drum and a marking member arranged to mark diagrams upon a strip of paper carried by said drum, the combination of an annular gear surrounding said drum and movable independently thereof; a ratchet movable with said gear; a plurality of rollers carried by said drum having operating pinions driven by said gear and adapted to regulate the movement of said strip of paper; a pawl adapted to be engaged with said ratchet to prevent the movement of said annular gear during an oscillation of said drum; a manually controlled device for moving said pawl into engagement with said ratchet; and means for disengaging said pawl from said ratchet at a predetermined time.

13. An engine indicator having an oscillating drum and a marking member arranged to mark diagrams upon a strip of paper carried by said drum, the combination of an annular gear surrounding said drum and movable independently thereof; a ratchet movable with said gear; a plurality of rollers carried by said drum having operating pinions driven by said gear and adapted to regulate the movement of said strip of paper; a pawl adapted to be engaged with said ratchet to prevent the movement of said annular gear during an oscillation of said drum; a spring for moving said pawl into engagement with said ratchet; means controlling the movement of said pawl and normally preventing its engagement with said ratchet; and means for actuating said controlling means.

14. An engine indicator having an oscillating drum and a marking member arranged to mark diagrams upon a strip of paper carried by said drum, the combination of an annular gear surrounding said drum and movable independently thereof; a ratchet movable with said gear; a plurality of rollers carried by said drum having operating pinions driven by said gear and adapted to regulate the movement of said strip of paper; a pawl adapted to be engaged with said ratchet to prevent the movement of said annular gear during an oscillation of said drum; a spring for moving said pawl into engagement with said ratchet; a rotatable cam controlling the movement of said pawl and normally pre-

venting its engagement with said ratchet; and means for actuating said controlling means.

15. An engine indicator having an oscillating drum and a marking member arranged to mark diagrams upon a strip of paper carried by said drum, the combination of an annular gear surrounding said drum and movable independently thereof; a ratchet movable with said gear; a plurality of rollers carried by said drum having operating pinions driven by said gear and adapted to regulate the movement of said strip of paper; a pawl adapted to be engaged with said ratchet to prevent the movement of said annular gear during an oscillation of said drum; a spring for moving said pawl into engagement with said ratchet; means controlling the movement of said pawl and normally preventing its engagement with said ratchet; a ratchet member revoluble with said controlling means; a manually controlled lever; and a pawl thereon coacting with said ratchet member.

16. An engine indicator having an oscillating drum and a marking member arranged to mark diagrams upon a strip of paper carried by said drum, the combination of an annular gear surrounding said drum and movable independently thereof; a ratchet movable with said gear; a plurality of rollers carried by said drum having operating pinions driven by said gear and adapted to regulate the movement of said strip of paper; a pawl adapted to be engaged with said ratchet to prevent the movement of said annular gear during an oscillation of said drum; a spring for moving said pawl into engagement with said ratchet; means controlling the movement of said pawl and normally preventing its engagement with said ratchet; a ratchet member revoluble with said controlling means; a manually controlled lever; a pawl thereon coacting with said ratchet member; and a pawl carried by said drum adapted in the oscillation of said drum to engage said ratchet wheel and move it about its axis.

17. An engine indicator having an oscillating drum and a marking member arranged to mark diagrams upon a sheet of paper carried by said drum, the combination of an annular gear surrounding said drum and movable independently thereof; a pair of paper gripping rollers carried by said drum provided with operating pinions driven by said gear; another freely revoluble roller carried by said drum around which the strip of paper passes on its way from the delivery spool to the periphery of said drum; and means for preventing the movement of said gear during an oscillation of said drum thereby effecting the feeding of said strip.

18. An engine indicator having an oscil-

lating drum and a marking member arranged to mark diagrams upon a sheet of paper carried by said drum, the combination of an annular gear surrounding said drum and movable independently thereof; a pair of paper gripping rollers carried by said drum provided with operating pinions driven by said gear; another freely revolute roller carried by said drum around which the strip of paper passes on its way from the delivery spool to the periphery of said drum; means for preventing the movement of said gear during an oscillation of said drum thereby effecting the feeding of said strip; a delivery spool for said paper; and a paper receiving spool driven by the movement of said drum in one direction.

19. An engine indicator having an oscillating drum and a marking member arranged to mark diagrams upon a sheet of paper carried by said drum, the combination of an annular gear surrounding said drum and movable independently thereof; a pair of paper gripping rollers carried by said drum provided with operating pinions driven by said gear; another freely revolute roller carried by said drum around which the strip of paper passes on its way from the delivery spool to the periphery of said drum; means for preventing the movement of said gear during an oscillation of said drum thereby effecting the feeding of said strip; a delivery spool for said paper; a paper receiving spool driven by the movement of said drum in one direction; and means interposed between said receiving spool and said drum adapted to take up the slack in said paper during the oscillatory movement of said drum.

40 20. An engine indicator having an oscillating drum and a marking member arranged to mark diagrams upon a sheet of paper carried by said drum, the combination of an annular gear surrounding said drum and movable independently thereof; paper gripping means carried by said drum and

operated by said gear when said drum oscillates independently thereof; a fixed gear on said drum; a receiving spool for said paper; a friction device for rotating said spool; a pinion thereon; a revolute gear meshing therewith; another revolute gear meshing with said fixed gear; and means interposed between said revolute gears adapted to rotate said pinion gear in one direction only.

21. An engine indicator having an oscillating drum and a marking member arranged to mark diagrams upon a sheet of paper carried by said drum, the combination of an annular gear surrounding said drum and movable independently thereof; paper gripping means carried by said drum and operated by said gear when said drum oscillates independently thereof; a fixed gear on said drum; a receiving spool for said paper; a friction device for rotating said spool; a pinion thereon; a revolute gear meshing therewith; another revolute gear meshing with said fixed gear; a ratchet secured to the latter revolute gear; and a spring pressed pawl secured to the other revolute gear engaging said ratchet wheel and causing the rotation of said pawl gear during the rotation in one direction only of said ratchet gear.

22. An engine indicator having an oscillating drum arranged to carry a strip of paper normally immovable thereon; means for oscillating said drum; a member carried by said drum but adapted to be restrained from rotation therewith; and feeding mechanism carried by said drum and coacting with said member to feed the paper when said member is restrained from rotation during the oscillation of said drum.

Signed by me at 4 Post Office Sq., Boston, Mass., this 27th day of August 1912.

EARL VAUGHAN.
